DESIGN FOR AN ATOMIZER

John Benniger, Cleveland, Ohio

Application May 16, 1935, Serial No. 56,859

Term of patent 7 years

To all whom it may concern:

Be it known that I, John Benniger, a citizen of the United States, residing at Cleveland, in the county of Cuyahoga and State of Ohio, have invented a new, original, and ornamental Design for Atomizer, of which the following is a specification, reference being had to the accompanying drawing, forming a part thereof.

In the drawing:

Fig. 1 is a front elevational view;

Fig. 2 is a side elevation; while

Fig. 3 is a top plan view of the atomizer showing my new design.

I claim:

The ornamental design for an atomizer as shown.

JOHN BENNIGER.
